UNITED STATES PATENT OFFICE.

MEYER LIEBMAN AND GEORGE E. DOUGHTY, OF NEW YORK, N. Y.

TRANSFER SYSTEM FOR DEPARTMENT STORES AND THE LIKE.

1,376,950.

Specification of Letters Patent.

Patented May 3, 1921.

Application filed March 11, 1918. Serial No. 221,821.

To all whom it may concern:

Be it known that we, MEYER LIEBMAN and GEORGE E. DOUGHTY, citizens of the United States, and residents of New York city, 5 county of New York, State of New York, have invented certain new and useful Improvements in Transfer Systems for Department Stores and the like, of which the following is a specification.

10 This invention relates to cards for facilitating shopping, especially in department stores, which devices are usually termed "transfer cards." The transfer system is a plan whereby a customer can go from 15 counter to counter, making a purchase at each, and have all the articles purchased brought to one central point in the store so that the customer can pay for them collectively and have them all packed together 20 to take home, or for delivery. This system obviates the trouble and delay incident to paying separately for articles purchased at each counter and facilitates delivery.

In carrying out a transfer system it is 25 necessary that the sales slips that accompany all purchases should have the same identifying mark, or that the packages should have the same identifying mark, and this mark must also appear on the transfer 30 card so that the articles may be collected and the purchaser identified with them. This has been accomplished in different ways, one scheme being to furnish the customer with a transfer card or book having 35 attached thereto a series of adhesive coupons all bearing the same number as the book and adapted to be torn off successively and pasted on to packages as purchased, or on to the sales slips accompanying the packages.

40 This system is rather expensive and troublesome to operate and the coupons are liable to become detached if carelessly applied to the slips or packages. Under another system the clerk simply marks each sales slip 45 by means of a pencil with the number or other identifying mark of the transfer card.

The present invention comprises a transfer system in which each transfer card bears 50 an identifying mark or number and is accompanied by some device to mechanically control the printing of a similar identifying mark or number on each package purchased, or, preferably, upon the sales slip attached to each package. The object of the mechanical control of the marking of the sales slips 55 or packages is to eliminate human errors, so

far as possible, from the transactions and thus avoid confusion and loss of time. The invention will be described in connection with the accompanying drawing, in which:— 60

Figure 1 is a view of a transfer card adapted to be used as a stencil to transfer its number to sales slips or packages;

Fig. 2 is a view of a similar card having perforations adapted to control the printing 65 of its number upon sales slips or packages by mechanical means;

Fig. 3 is a view of a transfer card having a stencil device attached thereto;

Fig. 4 is a view of a sales slip on which 70 the identifying number of the transfer card has been printed.

Referring to the drawing A indicates a transfer card having the usual lines and columns for inserting the details of purchases made by a customer and spaces for the name and address of the customer and an identifying number B cut out so that the card may be used as a stencil for printing this number on sales slips or packages. 75 On the card in Fig. 1 there is also shown the same number in print at C, but this may be omitted when the card is used as a stencil, as the stencil figures serve for identification.

In Fig. 2 is shown a card A' similar to 80 that shown in Fig. 1 excepting that perforations B' are provided to control any suitable mechanical means for printing the identifying number C'. When the perforations B' are used it is necessary to have printed on 85 the transfer card the identifying number C' which in the illustration is "1723." It will be understood that the perforations B' cause the printing of the number 1723 on the sales slip accompanying each package or directly 90 on the package.

Our invention may be carried out in various ways, and we have shown in Fig. 3 a form in which the stencil or other means for controlling the printing of the identifying 100 marks on the sales slips or packages is formed in sheet metal, such as thin tin or brass, to which may be attached a transfer card of the ordinary type. Referring to this figure, A² indicates the transfer cards, 105 and D a rectangular piece of sheet metal having cut or punched therein an identifying number or mark B² to form a stencil or perforations B³ to control the printing of the mark, or both. The card may be temporarily attached to the stencil sheet in any 110 suitable manner, as by prongs E cut from

the sheet. It will be understood that the sheet metal attachments to the cards may be used repeatedly, all of those used on any one day being usable on succeeding days indefinitely. Of course, those used during a single day or period of shopping must differ from each other.

Fig. 4 illustrates an ordinary sales slip to which the number of the transfer card shown 10 in Fig. 1 has been transferred by means of a pencil or ink brush, the number being indicated at F.

In using our transfer system a customer before making any purchase secures a card 15 and presents it at each counter where a purchase is made. The clerk notes the purchase on the card and makes out the usual sales slip and then uses the stencil or perforations on the card or on the sheet metal 20 attachment to control the printing of a similar identifying number or mark upon the package or, preferably, upon the sales slip. Where a simple stencil is used, as shown in Fig. 1, the clerk may trace the identifying 25 figures with a pencil inserted in the openings, or may use a brush and ink in the usual manner. Where machines are used, however, the card is inserted in the machine and the perforations will control the printing 30 of the identifying number, such as "1723," or the printing of identifying letters or groups of letters in a well known manner. The result in either case is obtained mechanically and it is practically impossible for the 35 clerk to make a mistake in placing the proper identifying marks upon the packages or sales slips attached thereto, and errors in the collection and delivery of purchases are thereby avoided. It will be un-

derstood that the means for mechanically 40 imparting the identifying mark of the transfer card to successive sales slips on parcels may be greatly varied in detail without departing from the spirit of our invention.

Therefore, without limiting ourselves to 45 the particular forms of the invention illustrated and described, we claim:—

1. In a transfer system for department stores and the like, a transfer card having an identifying mark, spaces for recording successive individual sales, and having incorporated therewith means to mechanically 50 control the printing upon successive individual slips or parcels, of an identifying mark corresponding to the mark on the card. 55

2. A transfer system for department stores and the like comprising a transfer card having spaces for recording successive individual sales and slips for recording the 60 respective sales, the card being provided with an identifying mark and with means for mechanically controlling the printing upon each of the slips of a corresponding identifying mark.

3. A transfer system for department 65 stores and the like, comprising a transfer card having spaces for recording successive individual sales and slips for recording the 70 respective sales, the card being provided with an identifying mark and with perforations for mechanically controlling the printing upon each of the slips of a corresponding identifying mark.

In testimony whereof we affix our signatures.

MEYER LIEBMAN.
GEORGE E. DOUGHTY.
